INSECT ELECTROCUTING TRAP

George H. Hill, West Boxford, Mass.

Continuation of design application Ser. No. 81,918, Sept. 29, 1964. This application Apr. 29, 1966, Ser. No. 2,060

Term of patent 14 years

(Cl. D31—3)

FIG. 1

FIG. 2

FIG. 1 is a front view in perspective of an insect electrocuting trap embodying my new design; and

FIG. 2 is a side view in perspective of the insect electrocuting trap of FIG. 1.

This application is a continuation of my copending application Serial No. D. 81,918, filed September 29, 1964, now abandoned.

I claim:

The ornamental design for an insect electrocuting trap, substantially as shown and described.
